UNITED STATES PATENT OFFICE

EDWIN LUNDGREN, OF FREDERICK, MARYLAND, ASSIGNOR TO INTERNATIONAL COMBUSTION ENGINEERING CORPORATION, OF NEW YORK, N. Y., A CORPORATION OF DELAWARE

BOILER FURNACE

Application filed February 17, 1926. Serial No. 88,756.

This invention relates to boiler furnaces and is especially useful where the fuel to be burned is in finely divided form such as pulverized fuel.

One of the primary objects of the invention is to greatly increase the capacity of a boiler of the cross drum type without materially increasing the size of the installation.

By my invention I propose by a novel arrangement of a cross drum boiler and a combustion chamber therefor to convert an ordinary cross drum boiler installation into a high capacity boiler installation, or construct a new installation from parts heretofore used in constructing the standard forms of boilers of this class.

The invention is particularly useful, although not necessarily restricted to, the converting of Babcock and Wilcox boilers in connection with which it will be described.

Other objects and advantages of my invention will be set forth hereinafter as they will be more readily understood in connection with the description of the invention.

How the foregoing, together with such other objects as may be incident to my invention, are realized is illustrated in preferred form in the accompanying drawings, wherein—

Fig. 1 is a vertical section through a boiler-furnace embodying the preferred form of my invention.

Fig. 2 is a plan section taken substantially on the line 2—2 of Fig. 1, and

Fig. 3 is a fragmentary section taken substantially on the line 3—3 of Fig. 1.

Referring now to the drawings and particularly to Fig. 1, it will be seen that I take a boiler of the cross drum type and preferably drop the two banks of tubes A, with their front and rear header *a* and *b* respectively, well below the cross drum B, and that a combustion chamber C is provided between the banks of tubes and the drum. The headers *a* and *b*, of which there is one front and one rear for each vertical row of the tubes A, may be of any standard form, either straight or sinuous.

The combustion chamber C is largely defined by tubular water walls as follows. The side walls 4 and 5 are formed of substantially horizontal finned tubes 6, connected into the vertical headers 7 and 8, the headers 7 being connected with the drum B by means of downcomers 9 and the headers 8 being connected with the drum B by the upcomers 10, headers 11, and upcomers 12. The rear wall 13 is formed of shielded tubes 14, which tubes connect the upper rear headers *b* of the bank of tubes A with the drum B. The tubes 14 are in this instance shielded by means of metallic blocks 15 which may be secured in position in any suitable manner. Thus it will be seen that these tubes may act as downcomers from the drum B to the rear headers *b* of the banks of tubes because the shielding thereof holds them at a lower temperature than the tubes A. In order to further insure adequate water flow to the headers *b* I also provide tubes 16 connecting the drum B with the lower portion of the headers *b* just mentioned, which tubes are shown outside of the combustion chamber. The front wall 17 of the combustion chamber C is formed of finned tubes 18 which connect the upper front headers *a* with the cross header 19, said tubes being upcomers. The top wall 20 is formed of finned tubes 21 which connect the cross header 19 with the drum B, said tubes being upcomers. The tubes A are marginal of the bottom of the combustion space, and it is pointed out that by virtue of the spacing of these rows of tubes passages are provided for the burnt products of combustion to pass through to the offtake 22, as well as any gravitating particles which may be removed from the settling chamber 23 through the opening 24. By inspection of the drawings it will be seen that suitable sheathing 25 is provided for the boiler furnace.

Referring now to the banks of tubes A, it is to be noted that they are of the usual construction as above pointed out, the banks of tubes, however, being separated a sufficient distance to provide space for the superheater 26. The headers *a* of the banks of tubes are connected by the finned upcomer 100

tubes 27 and the headers *b* thereof are connected by the finned downcomer tubes 28. In the particular arrangement shown in the drawings I have shown a greater number of tubes in the bank of tubes above the superheater 26 than in the bank of tubes therebelow, but it is to be understood that this may be varied to meet the particular superheat requirements of the installation. For example, if it should be desirable to obtain a high degree of superheat the number of tubes above the superheater would be reduced, from which it will be seen that the temperature of the superheat may be decreased or increased by employing either a greater number or a lesser number of tubes above the superheater. In this connection it is pointed out that the temperature of the combustion air preheater 29 located in the waste gas stack 30 may also be varied by changing the number of tubes in the banks.

The manner of introducing the fuel and combustion air to the combustion chamber to produce violent and intense combustion will now be described.

At the four corners of the boiler-furnace I have provided the burner nozzles 31 which deliver the pulverized coal in the combustion chamber in converging streams tangent to a circle about the longitudinal axis of the boiler furnace as diagrammatically indicated in Fig. 2. Combustion air is supplied around the burners 31 from the air heater 29 by means of the casing 32 as clearly shown in Fig. 2. I preferably introduce air at high velocity by means of fans (not shown) whereby the coal and highly preheated air so admitted produces a violently swirling vortical flame practically filling the combustion chamber cross sectionally, with the exception of the corners, where the fuel is admitted, the fuel and flame stream descending downwardly with the axis of the vortex substantially vertical. The preheated combustion air increases the furnace temperature head, and since the combustion chamber is defined by water tubes exposed to radiant heat there is a very rapid transfer of heat.

The products of combustion are drawn through the banks of tubes under the influence of the stack draft whereby the banks of tubes are subjected to the hot gases, the upper tubes, however, being exposed to radiant heat.

From the foregoing, it will be apparent that I am enabled to greatly increase the capacity of a cross drum boiler installation by so converting it into a boiler furnace, and this without materially increasing the size of the original installation.

It will be noted that the length of travel of the steam and water leaving the headers *a* is comparatively short, and thus, although

the tubes 18 and 20 are subjected to extremely high temperatures, there are neither circulation nor tube difficulties encountered.

While I have shown and described my invention as converting a Babcock and Wilcox cross drum boiler, it is to be understood that the advantages to be had through the practice of my invention may be had by converting other boilers of this general class.

What I claim is:—

1. A boiler furnace comprising in combination a boiler of the cross drum type having an upper drum, a bank of substantially horizontal tubes, and headers into which the tubes are connected, said bank of tubes and said headers being below the level of the drum, a combustion chamber substantially intermediate the level of the drum and said bank of tubes, means for introducing fuel and air under conditions to produce violent and intense combustion, and an offtake below said bank of tubes for drawing off the products of combustion, said combustion chamber including side walls formed of substantially horizontal water tubes, a rear wall formed of shielded vertical water tubes, a front wall formed of vertical finned water tubes, a top wall formed of substantially horizontal finned water tubes, said bank of tubes being marginal of the bottom of the combustion space, said combustion chamber defining tubes being connected in circulation with the cross drum boiler.

2. A boiler furnace comprising in combination a boiler of the cross drum type having an upper drum, a bank of substantially horizontal tubes, and front and rear headers into which the tubes are connected, said bank of tubes and said headers being below the level of the drum, a combustion chamber substantially intermediate the level of the drum and said bank of tubes, means for introducing fuel and air under conditions to produce violent and intense combustion, and an offtake below said bank of tubes for drawing off the products of combustion, said combustion chamber including side walls formed of substantially horizontal water tubes and their headers connected into the circulation of the aforesaid boiler, a rear wall formed of shielded water tubes connecting the rear headers of the aforesaid bank of tubes and the drum, a front wall formed of finned water tubes connecting the front headers of said bank of tubes and a header thereabove, and a top wall formed of substantially horizontal finned water tubes connecting the last mentioned header and the drum, said bank of tubes being marginal of the bottom of the combustion space.

3. The combination with a boiler of the cross drum type having an upper drum, a bank of tubes inclined from the horizontal, and front and rear headers into which the

tubes are connected, said bank of tubes and said headers being below the level of the drum, of a combustion chamber substantially intermediate the level of the drum and said bank of tubes, comprising side walls formed of tubes similarly inclined to the tubes of said bank, front and rear headers for said tubes, upcomers connecting the front headers with the drum, downcomers connecting the rear headers with the drum, a front wall formed of tubes connecting the front headers of the banks of tubes with a header thereabove, a top wall formed of tubes connecting the last mentioned header with the drum, a rear wall formed of tubes connecting the drum with the rear headers of the banks of tubes, still other tubes connecting the drum with said rear headers; suitable sheathing for the boiler furnace; means for introducing fuel to be burned in suspension in said combustion chamber, and an offtake below the banks of tubes for drawing off the products of combustion.

4. The combination with a boiler of the cross drum type having an upper cross drum, a bank of substantially horizontal tubes below the level of the drum, and front and rear headers into which said tubes are connected; of a combustion chamber substantially intermediate the level of the drum and said bank of tubes, said combustion chamber including side walls formed of water tubes connected in circulation with the cross drum boiler, a rear wall formed of water tubes connecting the rear headers of said bank of tubes with said cross drum, a front wall formed of water tubes connecting the front headers of said bank of tubes with a header thereabove, and a top wall formed of upflow water tubes connecting said last mentioned header with said cross drum; said last mentioned header being located below the level of said cross drum; and means for admitting fuel, into the combustion chamber to be burned in space.

In testimony whereof I have hereunto signed my name.

EDWIN LUNDGREN.
